US00D919700S

(12) **United States Design Patent** (10) Patent No.: **US D919,700 S**
Takeda et al. (45) Date of Patent: **** May 18, 2021**

(54) **THERMAL HEAD FOR A PRINTER**

(71) Applicants: **SATO HOLDINGS KABUSHIKI KAISHA**, Tokyo (JP); **KYOCERA Corporation**, Kyoto (JP)

(72) Inventors: **Yasuhide Takeda**, Saitama (JP); **Kazuya Shindo**, Kirishima (JP)

(73) Assignees: **SATO HOLDINGS KABUSHIKI KAISHA**, Tokyo (JP); **KYOCERA CORPORATION**, Kyoto (JP)

(**) Term: **15 Years**

(21) Appl. No.: **29/731,950**

(22) Filed: **Apr. 20, 2020**

CLAIM

We claim the ornamental design for a thermal head for a printer, as shown and described.

DESCRIPTION

FIG. 1 is a rear perspective view of the claimed design; FIG. 2 is a front perspective view of the claimed design of FIG. 1; FIG. 3 is a bottom perspective view of the claimed design of FIG. 1; FIG. 4 is a top view of the claimed design of FIG. 1; FIG. 5 is a bottom view of the claimed design of FIG. 1; FIG. 6 is a left side view of the claimed design of FIG. 1; FIG. 7 is a right side view of the claimed design of FIG. 1; FIG. 8 is a rear view of the claimed design of FIG. 1; and, FIG. 9 is a front view of the claimed design of FIG. 1. The broken lines shown in the drawings depict portions of the thermal head for a printer that form no part of the claimed design.

1 Claim, 8 Drawing Sheets
